UNITED STATES PATENT OFFICE.

HERMAN STEINMETZ, OF ROCHESTER, NEW YORK, ASSIGNOR TO BAT-A-PENY CORPORATION, OF ROCHESTER, NEW YORK.

AMUSEMENT DEVICE.

Application filed May 28, 1925. Serial No. 33,568.

The present invention relates to an amusement device and has for its object more particularly to afford improvements in game apparatus adapted to be played, preferably 5 in simulation of the game of baseball, and embodying means affording a variety of plays with mechanism for indicating the different plays made from time to time.

A further object of the invention is to 10 provide an improved amusement device embodying projectile throwing and guiding mechanism in which the projectiles may be driven at different speeds or with different degrees of force by the player, whereby they 15 are moved to different predetermined stations or positions in which each is adapted to control means for indicating its arrival at said positions.

A further object of the invention is to 20 provide an amusement device embodying projectile driving and controlling means including a series of play stations, one of which constitutes a preferred goal, from 25 which the projectile will be returned to the player and from others of which it is adapted to return to the driving means whereby it may again be driven in an attempt to reach said goal.

A further object of the invention is to 30 provide an improved amusement device embodying a plurality of play stations having different values, with electrically controlled indicating elements for the several stations included in circuits adapted to be closed by 35 projectiles directed and propelled by means under the control of the player, the successful operation of which is dependent more or less upon the player's skill in the control of the propelling means.

40 To these and other ends the invention resides in certain improvements and combinations of parts, all as will be hereinafter more fully described, the novel features being pointed out in the claims at the end of the 45 specification.

In the drawings:—

Figure 1 is a front elevation of a machine embodying the invention;

Figure 2 is a top plan view of the same;

50 Figure 3 is a front elevation with the door in open position, the game board being removed to illustrate the wiring arrangement for lamp circuits;

Figure 4 is a sectional plan taken on the 55 line 4^a—4^a of Figure 1;

Figure 5 is a view in elevation showing the manner of mounting the projectile throwing and controlling mechanism on the inner face of the door, the same being shown at normal inoperative position; 60

Figure 6 is a fragmentary elevation similar to the lower portion of Figure 5 with the projectile throwing lever moved to extreme release position;

Figure 7 is an elevation of the lower half 65 of the door shown in Figure 5 with the projectile throwing and circuit controlling means removed;

Figure 8 is a detail view in elevation, showing the rear face of the front guide 70 plate for the projectile, the contact pins being shown in section and in normal projectile receiving or circuit closing position;

Figure 9 is a sectional plan taken on line 9^a—9^a of Figure 5; 75

Figure 10 is a sectional plan taken on line 10^a—10^a of Figure 6;

Figure 11 is an enlarged detail fragmentary elevation showing one projectile in release position; 80

Figure 12 is a transverse sectional elevation taken on lines 12^a—12^a of Figures 1 and 8;

Figure 13 is an enlarged fragmentary elevation taken on lines 13^a—13^a of Figures 5 85 and 8;

Figure 14 is an enlarged fragmentary sectional elevation taken on lines 14^a—14^a of Figures 5 and 8;

Figure 15 is a sectional plan of the door 90 locking means taken on line 15^a—15^a of Figure 1, and

Figure 16 is a diagrammatic view of the 95 circuit arrangement for the electrical indicating system.

Similar reference numerals throughout the several views indicate the same parts.

The present invention embodying a game apparatus preferably includes a series of playing stations designed to simulate the 100 game of baseball, the indicating devices for the several stations or plays being electrically controlled or operated and preferably comprising different colored lamps which become lighted when the projectile, driven by suitable means under the control of the player, reaches certain predetermined circuit closing positions. A white light preferably indicates the home-run position for the projectile the latter preferably constituting a 110

penny or a properly constructed disk formed of any suitable conducting material, which when thrown by the driving means to any of the positions provided will form a circuit closing member and effect the lighting of the lamps corresponding to said positions. The first, second and third bases have both blue and red lights, the latter indicating that the player was unsuccessful, in which case the projectile falls into the casing to a point from which it is not accessible. However, when the blue lamps are lighted they each indicate a "safe" position and the player is afforded another chance, since the mechanism is such that upon release of the projectile from any of said "safe" positions it will return by gravity to the driving member whereby the operator is entitled to additional plays as often as the blue lamps are successively lighted. The more important plays of the game of baseball are therefore simulated and if desired other plays may be added without departing from the spirit of the invention.

The particular means employed for practicing the invention preferably comprises a base 10 supporting a casing 11 including a closure 12 which is preferably of the hinged type and upon which the projectile driving and circuit closing devices are mounted. The white or home-run lamp is indicated at W while the first, second and third base blue lamp, each indicating a "safe" play, are shown at B¹, B² and B³, respectively. The three red lamps for indicating unsuccessful plays at the first, second and third bases are indicated, respectively, at R¹, R² and R³. All of the lamps are projected through a board 20 preferably supported by the lamps and having painted or otherwise formed thereon the outlines of a baseball diamond as indicated at 21 in Figure 1, the white and blue lamps being shown on the bases while the red lamps are disposed adjacent the same.

Current for the lamps is supplied by one or more dry batteries, preferably two as indicated at 22, the upper ends of the batteries being disposed between the end walls 50 of the casing and an inwardly projecting central wall portion 24 as shown in Figures 3 and 4, suitable clamping members 25 being provided for holding the batteries in position.

The lamps are screwed into suitable sockets 26 secured upon the rear wall of the casing behind the lamp board 20 as shown in Figure 12 and provided each with a pair of binding posts 27 engaging contact plates, not shown and by which the wires are connected with the lamps.

The projectiles used with the apparatus, one of which is indicated at 28, are of a predetermined size and are controlled by the front and rear guide plates 29 and 30 which

preferably have extensions projected thru the end wall of the closure to form the projectile receiving opening 31. From this opening the projectile drops to the position indicated at 28^a in Figure 5, being directed to said position partly by an inclined laterally projecting rib 32 on the plate 29. The projectile is temporarily held in said position by a pin or projection 33 extended through a slot 34 in the rear plate 30 and connected with a suitable driving member, preferably in the form of a lever 35 pivoted at 36 upon the plate 30 and having a finger piece 37 projected through a slot 38 in the closure to permit the lever to be depressed and released by the player at different points. The lever is normally held in the position shown in Figure 5 by a spring 39 which is relatively strong and serves as an actuating member for the lever whereby the projectile may be driven with different degrees of force or at different speeds, depending upon the point at which the lever is released by the player, its lowest release position being indicated in Figure 6 where the projectile is shown resting upon the pin 33 in a recess 40 of the guide plates. A guide bar 41 serves to hold the lever in the desired plane of operation, the guide bar being suitably secured upon the rear plate 30 as indicated in Figure 5. The lever carries an angularly disposed arm 42 provided for a purpose which will hereinafter appear.

The projectile is thrown by the lever upwardly between two transparent guide plates 43 and 44, preferably glass, disposed in front of the lamp board 20 whereby the lamps and the field 21 are rendered visible at all times. The glass plates are spaced apart a distance but slightly greater than the thickness of the projectile so that the latter will continue to move in a vertical plane after being discharged by the driving means. The path of the projectile will vary according to the force with which it is thrown, which is dependent upon the point at which the lever or driving member is released as will be understood, the dotted line 44^a in Figure 5 indicating by way of example the approximate path of the projectile when moving to one of the circuit closing positions to which it may be driven. In this connection seven predetermined positions are provided, constituting points to which the projectiles may descend by gravity when fired by the player, each comprising a "play station" corresponding to one of the lamps or indicating members of the system. These stations are indicated successively from left to right in Figures 5 and 6 by the characters B^{1'}, B^{2'}, R^{1'}, W', R^{2'}, B^{3'} and R^{3'}, corresponding respectively to the lamps B¹, B², R¹, W, R², B³ and R³, as shown in Figures 3 and 16. The projectiles when at the stations shown successively from left to right

in Figure 5 are adapted to engage movable contacts represented by the numerals 13 to 19 inclusive, and at the same time engage fixed contacts 13' to 19' inclusive which are 5 preferably in the form of laterally projecting ribs on the front plate 29, forming guide-ways corresponding respectively to the indicating stations B¹, B², R¹, W, R², B³ and R³. The projectiles when released from circuit 10 closing position by movement of the contacts 13 to 19 inclusive from right to left as viewed in Figure 6 are disposed of in a manner hereinafter explained. The movable contacts 13 to 19 inclusive are carried by a 15 bar 45 formed of suitable insulating material and mounted upon a slide 46 disposed upon the rear face of the plate 30 and supported by a pair of lugs 47 projecting from said plate into slots 48 of the slide, the latter 20 being held by washers 49 secured by screws 50 as best shown in Figure 14. The slide 46 is normally held in the position shown in Figure 5 by the arm 42 of the driving lever 35, the arm having a rubber or fiber block 51 25 adapted to prevent excessive noise in operation upon release of the lever from any of its depressed positions. When the lever is depressed the slide 46, bar 45 and contacts 13 to 19 are all moved automatically to the 30 left by a spring 52 having one end connected with the slide and the other with a lug 53 projecting rearwardly from the plate 30. The extent of movement of the slide is determined by the length of the slot 48 which is 35 only slightly greater than the length of the lugs 47 therein, the movement being sufficient to carry the contacts to the left as viewed in Figure 8 far enough to permit the projectiles 28 to clear the contacts as indicated in 40 Figure 11 so that they may drop to the desired point. It will be seen therefore that the discharge of the projectiles from any one of the circuit closing positions will be effected by the action of the spring 52 im- 45 mediately upon movement of the lever 35 to release position. However, since the lever actuating spring 39 is considerably stronger than spring 52 the slide 46 will be returned to the position shown in Figure 5 when 50 struck by the lever arm 42 and in time to return the movable contacts to position to arrest the movement of the projectiles thrown by the lever to one or another of the several stations provided. The path of the projectile will of course be determined to a 55 certain extent by the force with which it is thrown but since it is given an initial movement in a curved path by reason of being moved in contact with the curved or inclined surface 54 of the plate 29 it is more effectively controlled and directed in its movement above the several stations, to which it descends by gravity. In this connection the 60 surface 55 of the plate 29 may also be relied 65 on to deflect or direct the projectile so as to

insure its movement from right to left as viewed in Figure 5 to the farthest as well as the nearest of the stations provided. It will be seen therefore that the number of 70 home-run or white light positions which the player can make with a given number of shots will depend largely upon his skill in determining the correct position at which to release the driver, as well as in the manner in which it is released, since a quick or 75 sudden release will afford different results from that obtained through a more gradual release.

From any of the three red light stations indicated at R¹, R², and R³ in Figure 5, 80 the projectiles, upon being released by the movable contact members are discharged into the casing, being deflected therein thru openings 56 in the rear plate 30 by the inclined surfaces 57 as shown in Figures 5 85 to 8 inclusive.

From any of the three blue light stations B¹, B² and B³ the projectiles when released are adapted to drop upon an inclined track 58 on the front plate 29 and to roll 90 into engagement with the driving pin 33 as shown in the lower left hand corner of Figure 5, thus affording the player another shot with the same projectile and also additional shots, as long as the projectile is successively 95 returned to the blue light stations.

When the projectile is thrown to the home-run position, indicated by the white light station W, it is returned to the player through slot 59, passage 60 and opening 61 100 in the bottom of the closure to the recess 62 formed in the base 10 of the machine. The passage 60 below the plate 29 is closed at the rear by a cover plate 63 spaced from the inner face of the closure by a pair of ribs 64, 105 the cover plate being secured by means of the screws 65 as shown in Figure 7. Slots 67 and 68 are provided in the front and rear guide plates 29 and 30, respectively, to permit movement of the contact pins 13 to 110 19 inclusive to and from release position.

The circuit wires leading from the contacts 13 to 19 are disposed within a groove 69 formed in the rear face of the sliding bar 45, each wire preferably having its end 115 clamped between a pair of washers 70 secured by the contact pins as shown in Figures 13 and 14. The wires are carried from the left hand end of the slide bar 45 thru a flexible covering 71 as shown in Figure 3 to 120 the lamps, the several circuits of which will be readily understood from the diagrammatic arrangement shown in Figure 16.

The glass panels 43 and 44 through which the course of the projectile is visible are 125 preferably adapted to rest upon the upper edges of the plates 29 and 30, respectively, as shown in Figure 12. Spacing strips 72 serve to hold the glass plates apart while vertical strips 73 are provided for clamping 130

the glass in position as shown in Figures 4 and 5.

A strip 74 is disposed inwardly of the glass 44 at the base thereof and provided with data by which the player may readily locate the different stations and understand the values of the same.

The door 12 which is hinged at 75 is provided with a suitable lock as indicated in Figure 15, which preferably comprises a bolt 76 threaded into a lug 77 on the door and having its head 78 provided with an extension 79 carrying one or more laterally projecting pins 80. A key, not shown, is adapted to be inserted in the recess 81 of the extension and is provided with slots to receive the pins whereby the bolt may be screwed into or out of locking position when desired. If preferred the machine may be further protected by a seal 82, the wire 83 of which is passed through a closure 84 for the recess 81 and through the outer end 85 of the wall surrounding the recess.

While the machine may be operated without the use of the particular form of indicating elements provided for the several stations to which the projectiles may be driven, or if desired without the use of any electrically controlled indicating elements, I prefer to employ the different colored lamps in the manner shown in order to afford a more attractive and complete machine, whereby the interest of the player is increased and the value of the machine as an entertaining medium enhanced.

I claim as my invention:

1. In an amusement device, a plurality of electric circuits, a series of station indicating devices adapted to be controlled by said circuits and releasable projectile driving means for elevating projectiles in a plane to permit them to drop in said plane to points at which they will act to complete the circuits whereby the indicating devices are operated.

2. In an amusement device, a plurality of electric circuits, including a series of contacts, a movable holder for said contacts, a series of station indicating devices adapted to be controlled by said circuits, manually operable projectile driving means movable for release at different points whereby to drive projectiles at different speeds directly to points at which they will engage said contacts and act to complete the circuits and effect operation of the indicating devices, said driving means normally forming a guard for said holder and means for moving the holder to release the projectiles upon movement of the driving means from normal position.

3. In an amusement device, a plurality of normally open electric circuits, a series of station indicating devices adapted to be operated by said circuits, projectile driving

means for moving projectiles at different speeds without interruption in a vertical plane to different circuit closing positions, the particular position to which each projectile is moved depending upon the speed at which it is driven, means for releasing the projectiles from circuit closing positions and means for returning the projectiles to the driving means when released, said releasing means being under the control of the driving means.

4. In an amusement device, a plurality of electric circuits, a series of station indicating devices adapted to be controlled by said circuits, projectile driving means for moving projectiles with different degrees of force in unobstructed paths to points at which they will act to complete the circuits whereby the indicating devices are operated and transparent guide means for the projectiles through which the indicating devices are visible.

5. In an amusement device, a plurality of electric circuits, a series of station indicating devices adapted to be controlled by said circuits, projectile driving means for moving projectiles without interruption to points at which they are adapted to effect control of the circuits whereby the station indicating devices are operated, and means permitting the return of the projectiles to the player from one of said points.

6. In an amusement device, a plurality of normally open electric circuits having separate circuit closing positions, a series of station indicating devices adapted to be included in said circuits and operable when the circuits are closed, means for driving projectiles at different speeds without interruption to said closing positions, and transparent guide means for the projectiles through which said indicating devices are visible.

7. In an amusement device, a plurality of normally open electric circuits each having a separate circuit closing position, a series of station indicating lamps adapted to be included in said circuits for indicating a plurality of play stations in a single plane, a projectile and means effective to drive the projectile directly in said plane to any one of said circuit closing positions.

8. In an amusement device, a plurality of normally open electric circuits each having a separate circuit closing position, a series of station indicating elements adapted to be included in said circuits, a projectile, means adapted to guide the projectile in a plane coincident with said positions and means for driving the projectile upwardly in said plane to permit it to drop to any one of said positions.

9. In an amusement device, a plurality of normally open electric circuits, a series of station indicating elements adapted to be in-

cluded in said circuits, a projectile for closing one of said circuits, a driving member for the projectile having a variable throw and means for guiding the projectile in a 5 vertical plane without interruption to one of said circuit closing positions.

10. In an amusement device, a plurality of normally open electric circuits, a station indicating element for each circuit adapted to 10 be operated upon closing the circuit, a projectile, and driving means for selectively moving the projectile with a variable degree of force without interruption upwardly in a plane to permit it to drop in said plane 15 to different circuit closing positions whereby to effect operation of the station indicating elements.

11. In an amusement device, a plurality of normally open electric circuits each having 20 a predetermined circuit closing position, a station indicating element for each circuit adapted to be operated upon closing the circuit, a projectile, driving means for selectively moving the projectile with a variable 25 degree of force whereby it will be driven to one of said circuit closing positions and means permitting the projectile to return to the driving means from one of said positions.

12. In an amusement device, a casing, a 30 plurality of electric circuits each provided with a separate control station, an indicating element within the casing for each circuit adapted to be operated thereby, a projectile adapted when moved to any of said 35 stations to effect operation of the indicating element corresponding thereto, driving means for throwing the projectile whereby it is adapted to drop by chance to one of said control stations, means whereby the 40 projectile is returned to the driving means when released at one of said stations and means adapted to cause the projectile to return to the player when released at another of said stations.

45. 13. In an amusement device, a casing, a plurality of electric circuits each provided with a separate control station, an indicating element within the casing for each circuit adapted to be operated thereby, a projectile adapted when moved to any of said 50 stations to effect operation of the indicating element corresponding thereto, driving means for throwing the projectile whereby it is adapted to drop by chance to one of said control stations, means whereby the 55 projectile is returned to the driving means when released at one of said stations, means adapted to cause the projectile to return to the player when released at another of said 60 stations, and means adapted to effect discharge of the projectile into the casing when released at another of said stations.

14. In an amusement device, a casing, a plurality of normally open electric circuits

each having a separate control station including a fixed contact, a movable contact and an indicating element operable when the circuit is closed through said contacts, a carrier for said movable contacts, a projectile, manually releasable driving means for the projectile having a variable throw whereby the projectile may be moved to either of said control stations to complete the circuit through the contacts thereof, and means under the control of the driving means for actuating 75 said carrier to effect release of the projectile from engagement with said contacts when the driving means is moved to a predetermined position.

15. In an amusement device, a casing, a closure therefor, a plurality of station indicating elements secured within the casing, electric circuits for operating said elements, each including a pair of spaced contacts, a projectile, vertically disposed guides 85 for the projectile carried by the closure and manually releasable means for driving the projectile between said guides, said driving means having a variable throw whereby the projectile may be moved to complete 90 either of said circuits through engagement with the contacts thereof.

16. In an amusement device, a plurality of electric circuits each having a separate control station including a fixed contact, a 95 movable contact and an indicating element operable when the circuit is closed through said contacts, a carrier for said movable contacts, a projectile, spaced members for guiding the projectile in a vertical plane and 100 means for driving the projectile between said spaced members without interruption to one of said stations.

17. In an amusement device, a plurality of electric circuits each having a separate 105 control station including a fixed contact, a movable contact, and an indicating element operable when the circuit is closed through said contacts, a carrier for said movable contacts, spaced guides above said stations, 110 a projectile, a spring controlled operating lever for the projectile adapted to drive it between said guides to one of said stations, and means under the control of the lever for moving the carrier to effect release of the projectiles when the lever is moved from normal inoperative position.

18. In an amusement device, means forming a plurality of play stations, spaced members for guiding projectiles in a vertical plane above said stations, manually controlled means for driving the projectiles between said spaced members to said stations, means effective to return the projectiles to the operator from one of said stations, and means by which the projectiles are returned to the driving means from another of said stations.

19. In an amusement device, a casing, means within the casing forming a plurality of play stations, spaced members for guiding projectiles in a vertical plane to said stations, manually operable means for driving the projectiles between said members to the stations, means for directing the projectiles from one of said stations into the casing, means for directing the projectiles from another of said stations to a point accessible to the operator, and means by which the projectiles are returned to the driving means.
20. In an amusement device, a casing, projectile control means within the casing embodying plate members having a series of vertically disposed projectile receiving and discharge passages, one of which is adapted to discharge the projectiles into the casing and another to direct them to the exterior of the casing, means for driving the projectiles in a vertical plane directly to said receiving passages, and releasable means for temporarily holding the projectiles within said receiving passages.
21. In an amusement device, a casing, projectile control means within the casing embodying plate members having a series of vertically disposed projectile receiving and discharge passages, one of which is adapted to discharge the projectiles into the casing and another to direct them to the exterior of the casing, means for driving the projectiles in a vertical plane directly to said receiving passages, releasable means for temporarily holding the projectiles within said receiving passages, and means for indicating the arrival of the projectiles in said passages.
22. In an amusement device, a casing, manually controlled projectile driving means therein, projectile control means within the casing embodying plate members having a series of projectile receiving and discharge passages, one of which is adapted to discharge the projectiles into the casing, and another to return them to the operator while another is adapted to return the projectiles to the driving means.
23. In an amusement device, a casing, manually controlled projectile driving means therein having an operating portion projecting from the casing, plate members within the casing forming a plurality of projectile receiving stations, vertically disposed guide members for directing projectiles propelled by said driving means to said stations, releasable means for temporarily arresting the projectiles at said stations adapted to automatically move to release position upon movement of the driving means from normal inoperative position, means for directing the projectiles into the casing from certain of said stations, and means effective to return the projectiles to the driving means from other of said stations.
24. In an amusement device, a plurality of normally open electric circuits having a series of illuminating elements for indicating a plurality of play stations, a projectile for closing each of said circuits when moved to different predetermined positions, manually operable driving means for moving the projectile directly to circuit closing positions, said driving means being releasable at different points whereby to vary the circuit closing position to which the projectile is driven and means for returning the projectile directly from one or more of said positions to said driving means.
25. In an amusement device, a plurality of normally open electric circuits having a series of illuminating elements for indicating a plurality of play stations, a projectile adapted to close each of said circuits when moved to predetermined positions with respect thereto, a releasable spring operated driver for the projectile having a variable throw whereby to vary the circuit closing position to which the projectile is driven, and means under the control of said spring operated driver for releasing the projectiles from certain of said stations.
26. In an amusement device, means forming a plurality of play stations adapted for receiving a projectile, spaced guide members for the projectile disposed vertically above said stations, a driving device for the projectile having a variable throw and adapted in each driving operation to direct the projectile upwardly between said guide members in a path inclined to the vertical whereby the projectile will have a horizontal component movement throughout its travel to the different stations and means effective to return the projectile from one of the stations to said driving device.
27. In an amusement device, an electric current supply source, a plurality of normally open electric circuits having a series of illuminating elements for indicating a plurality of play stations located in a single vertical plane, a projectile adapted to close each of said circuits when moved to a predetermined position with respect to said stations, spaced guide members for maintaining the projectile in said plane unobstructed in its movement to said stations and a driving device for the projectile having a variable throw and adapted in each driving operation to direct the projectile upwardly between said guide members in a path inclined to the vertical whereby said projectile will have a horizontal component movement throughout its travel to the different circuit closing positions.
